Primary Examiner — Rhea Shields

(74) Attorney, Agent, or Firm — Thomas | Horstemeyer,
LLP(57) CLAIM

The ornamental design for a floor lamp, as shown and described.

DESCRIPTION

1.1 is a top perspective view;
1.2 is a bottom perspective view;
1.3 is a side view;
1.4 is side view;
1.5 is a top view; and
1.6 is bottom view.
The broken lines shown in the drawings illustrate portions of the floor lamp that form no part of the claimed design.
